[57] CLAIM

The ornamental design for a wall mountable caddy, as shown and described.

DESCRIPTION

FIG. 1 is a perspective view of a wall mountable caddy showing our new design;

FIG. 2 is a front elevational view thereof;

FIG. 3 is a top plan view thereof;

FIG. 4 is a left side view thereof, the opposite side being a mirror image of the side shown;

FIG. 5 is a rear elevational view thereof; and,

FIG. 6 is a perspective view of an alternative embodiment thereof.

The suction cup has been omitted in FIG. 5 for clarity of illustration.
